UNITED STATES PATENT OFFICE

JAMES B. SCHaub, OF WILMETTE, ILLINOIS, ASSIGNOR TO T. W. SNOW CONSTRUCTION CO., OF CHICAGO, ILLINOIS, A CORPORATION OF ILLINOIS

MATERIAL-MOVING APPARATUS

Application filed June 23, 1927. Serial No. 200,993.

My invention relates to material-moving apparatus, in general; but more especially to apparatus in which the material to be moved is positioned in a hopper from which the material is dischargeable to material-moving means, as for example a movable receptacle, for transferring the material to another location, as for example from a hopper located below a railroad track and provided to receive cinders from a locomotive, to a point of discharge above a cinder-receiving car.

My primary object generally stated is to provide novel and simple improvements in apparatus of the general character above stated to the end that the apparatus may be rendered more compact and more economical of construction and function in an improved manner. Certain of my specific objects are to provide such a construction of apparatus of the general character stated, and in which the movable receptacle is caused to travel from a substantially horizontal path through a substantially vertical path, that it will occupy the minimum amount of space, which is of especial importance where the apparatus is used as a part of railway track equipment where it is necessary to conserve space to the maximum; to provide a construction of apparatus of the general character stated in which the various tracks including those by which the receptacle is caused to become positioned for dumping, are arranged, at each side of the apparatus in alignment, thereby economizing in the cost of construction; to provide for a simple arrangement of tracks of such form that the receptacle may move to dumping position, without requiring the rollers thereon to be offset laterally relative to each other, and without involving the movement of the rollers in intersecting paths; to provide an arrangement of parts whereby cross-shafts for guiding rollers so positioned as to be engaged by the material discharged into the bucket, are dispensed with; to provide such a construction of bucket of the type adapted to receive the material when positioned on its side and when turned on its end to retain and carry the material, that it affords a chute portion at its discharge end and in use the spilling of

the material from the bucket in the loading thereof and its movement toward discharging position, will be prevented; to provide a bucket of this type of such form and construction that the curved portions of the tracks along which it moves from filling to raising position, may be made relatively abrupt and thereby economize in the space occupied by the apparatus; to provide such a type of bucket in which allowance for variations in the angle at which the material becomes reposed in the bucket at the discharge end thereof, to avoid spilling of the contents of the bucket, may be reduced to the minimum, and thus permit of the use of a relatively short bucket for any given load, thereby not only reducing the cost of constructing the bucket but also aiding, as one of the factors, in permitting of the use of abruptly curved track portions at the lower ends of the upwardly extending tracks; to provide for such an arrangement of tracks and cooperating bearing members on the bucket in an apparatus of the general type above stated, that the discharge, chute, portion of the bucket may be caused to extend outwardly from the track-equipped tower portion a relatively great distance, in the discharging position of the bucket, without requiring the supporting of the load of the bucket at any time at a relatively great distance from the upwardly extending tracks and the supporting of this load closely adjacent to, and preferably within, the confines of the tower, in the final dumping position of the bucket; and other objects as will be manifest from the following description:

As a preface to the following description, it may be stated that I have devised my improvements for embodiment, more particularly, in so-called cinderizing apparatus, adapted to receive, and dispose of, the cinders discharged from locomotives during the cleaning out of the fire boxes thereof, and thereafter elevate the cinders to a point of discharge above a track upon which the cinder-receiving car runs, and have, therefore, chosen to illustrate it in such an apparatus.

Referring to the accompanying drawings:

Figure 1 is a view in sectional elevation of a plant of the character stated and embodying my improvements. Figure 2 is an enlarged broken section taken at the irregular line 2—2 on Fig. 1 and viewed in the direction of the arrows. Figure 3 is a broken view in side elevation of the tower portion of the apparatus. Figure 4 is an enlarged plan sectional view of the three tracks shown in Fig. 3, the section being taken at the line 4—4 on Fig. 3 and viewed in the direction of the arrows. Figure 5 is a view like Fig. 1 of a modification of the structure shown therein; and Figure 6, a view, partly in section and partly in elevation, of the apparatus shown in Fig. 5, that portion of the apparatus which is shown in elevation being viewed from the left-hand side of this figure and that part which is shown in section being viewed along the line 6—6 on Fig. 5 in the direction of the arrows.

In the particular arrangement shown in Figs. 1 to 4, inclusive, a railway track for receiving the locomotives to be discharged of their cinders, is represented at 10 and a track upon which the cinder-receiving car is to run, at 11. Located below the track 10 is a pit 12 which extends laterally beyond this track at both sides thereof. Located in the space between the rails forming the track 10, and positioned in the upper part of the pit 12, is a hopper 13 into which the cinders discharged from the locomotives positioned thereover, dump, the bottom of this hopper being open to provide a discharge outlet controlled by gates as hereinafter described.

The receptacle for receiving the cinders from the hopper 13, and shown in the form of a bucket, is represented at 14, its upper side, considering the bucket as positioned on its side for filling, being open part way from the right-hand end thereof in Fig. 1, to receive therethrough the cinders from the hopper, when the bucket is positioned beneath the latter as shown in Fig. 1. The bucket 14 is movable, under control, in a direction crosswise of the track 10 and upwardly in righted condition along a tower portion 15 to a point of discharge as represented by the dotted, dumping, position of the bucket in Fig. 1 in which position the material elevated by the bucket discharges into a cinder car (not shown) on the track 11.

The bucket 14 is provided at its closed end, (namely, the left-hand end of Fig. 1) with rollers 16 arranged at opposite sides of, and in spaced relation to, the opposite sides of the bucket and above the lower side of the bucket, viewing it in Fig. 1, as shown in this figure and in Fig. 2, these rollers being shown as journalled on a shaft 16^a, secured in any suitable way, to the bottom portion of the bucket. The side of the bucket opposite that containing the opening through which the

material is discharged into the bucket, and which side extends lowermost when the bucket is positioned as shown in Fig. 1, inclines toward the opposite, open, side thereof, namely, upwardly in Fig. 1, as represented at 17, and located adjacent this inclined portion and at opposite sides of the bucket, and in a plane below the rollers 16 (viewing the bucket in Fig. 1,) are rollers 18 shown as supported on a shaft 19 extending crosswise of, and connected with, the tapering side 17 of the bucket. The bucket is also provided with another set of rollers represented at 20 located at opposite sides thereof with their upper surfaces (in Fig. 1) approximately in line with the upper surfaces of the rollers 18, all of the rollers 16, 18 and 20 being in alignment at opposite sides of the bucket as shown in Fig. 2.

The various rollers referred to cooperate with supporting and guiding double rail tracks which are located in the pit 12 and extend upwardly therefrom into the tower portion 15, these tracks being represented at 21, 22 and 23 and located at opposite sides of the pit and tower. The portions of these tracks which are located in the pit and extend beneath and to opposite sides of the hopper 13 are positioned substantially horizontally and parallel with each other in spaced relation as shown. At their forward ends each inclines abruptly upwardly and away from the hopper 13 as represented at 21^a, 22^a, and 23^a, the lower ends of these inclined track sections where they connect with the front ends of the horizontal sections thereof being abruptly curved as shown. The upper ends of the inclined track sections 21^a and 22^a connect with the lower ends of vertical track sections 21^b and 22^b of the tracks 21 and 22 which extend upwardly in the tower portion 15 to a point adjacent the upper extremity of the latter. The upper end of the inclined double rail track section 23^a connects, at opposite sides of the tower, with the lower end of a double rail track section 23^b, forming a part of the track 23, the lower end of which, represented at 23^c, inclines downwardly and outwardly as shown, and the upper end of which represented at 23^d inclines upwardly and outwardly and terminates in a substantially horizontal double track portion 23^e located some distance below the upper ends of the track sections 21^b and 22^b, the portion of the track section 23^b intermediate the portions 23^c and 23^d thereof being vertical and parallel with the track sections 21^b and 22^b. Located directly above the track portion 23^d, at opposite sides of the tower and in spaced parallel relation with this track portion is a double rail track section 24 which extends substantially from the track section 22^b to the upper ends of the straight track portion 23^d; and located above the track 24, at opposite sides of the tower, is a double rail track

ratus may be made very compact, as distinguished from constructions wherein the bucket is required to move through a long sweeping turn in moving into and out of its vertical path of movement, this feature being of particular importance where the apparatus is to be installed along railway road-beds where the space available for such installations is usually quite meager and furthermore results in reduced cost of construction.

It will be noted that by constructing an apparatus in accordance with my invention the discharge portion of the bucket may be caused to extend laterally beyond the tower as shown by dotted lines in Fig. 1, a relatively great distance without requiring that the load imposed by the bucket on the supporting structure along which the bucket travels, be supported at any time a relatively great distance from the tower and furthermore permits of the supporting of such load within the confines of the tower in the final dumping of the bucket. This is made possible by reason of the provision of three sets of rollers and the arrangement of the tracks as shown and described, whereby the bucket is supported by the rollers 18 only during the beginning of the dumping movement and during the latter part of the righting movement of the bucket, and the rollers 20, co-operating with the track 25, support the bucket during the latter part of the dumping movement and the beginning of the righting movement. The rollers 18 may thus be positioned at a remote distance from the discharge end of the bucket and a track section 23^e of relatively short length as shown may be used, as distinguished from a construction in which the bucket is supported throughout its turning movements on a single set of rollers.

As regards the feature of providing the bucket with an inclined side 17, a bucket so formed not only provides a clearance serving the purpose hereinbefore recited, but also reduced the need, in the designing of the bucket, of allowing for as great variations in the angles of repose of the material at the discharge end of the bucket, as is necessary in the case of buckets the corresponding side portion of which, in the filling position of the bucket, extends substantially horizontally, it being noted that where such side of the bucket is substantially horizontal the distance therefrom to the top of the material superposed thereon is much greater adjacent the discharge outlet than in the case of a bucket formed in accordance with my invention, this being a matter of considerable practical importance as the angles of repose of different kinds of material and material in different conditions, varies, and allowance therefore must be made in designing the bucket to avoid spilling of the contents thereof in the movement of the bucket to the path in which it travels upwardly; this feature also being

of importance as it permits of the bucket being made shorter for any given load. Another advantage resulting from the inclined side wall portion as referred to is that it permits of the loading into the bucket of wet material without the risk of the material running out of the discharge end of the bucket.

Referring to the structure shown in Figs. 5 and 6 and which presents the features of advantage above pointed out, the arrangement therein shown is substantially the same as that shown in the preceding figures, except that the track portions 21, 22 and 23 instead of being horizontal, incline slightly downwardly away from the tower portion, and a different type of tower and a different hoisting means are provided. The type of tower shown in these figures need not be described inasmuch as it does not constitute any feature of my invention and the construction thereof appears to be obvious. As regards the hoisting mechanism, provision is made for controlling the bucket by a lift cable, as distinguished from the endless sprocket chain arrangement of the preceding figures. This lift cable mechanism comprises cables 100 and 101 which connect with the shaft 16^a at opposite sides of the bucket 14 and thence extend around pulleys 102 and 103 and upwardly around pulleys 104 and 105, respectively, and thence down to the drum 106 of a hoisting mechanism represented generally at 107, it being understood that the bucket is raised to the dotted dumping position shown in Fig. 5 by drawing up on the cables 100 and 101, and is permitted to lower to the full line position shown in this figure by slackening these cables.

While I have illustrated and described certain particular embodiments of my invention I do not wish to be understood as intending to limit it thereto as the invention may be utilized in other embodiments without departing from the spirit thereof.

What I claim as new, and desire to secure by Letters Patent, is:

1. In apparatus of the character described, the combination of a bucket, and bucket guiding means along which said bucket is movable, so constructed and arranged that when the bucket is in lowermost, filling, position it is positioned on its side and in moving along said means moves toward righted position, one side of said bucket being partly closed and the opposite side thereof inclining toward said partly closed side and toward the discharge end of the bucket, said partly closed side extending from the base of the bucket upwardly above the beginning of the inclined portion of said opposite side.

2. In apparatus of the character described, the combination of a bucket, and bucket guiding means along which said bucket is movable, so constructed and arranged that when the bucket is in lowermost, filling, position it

25 presenting a downwardly and outwardly inclined double rail section 25^a which extends from the track section 22^b outwardly to a point in substantial alignment with the track section 24, but in vertically spaced relation to the latter as shown, the rear end of the track 25 terminating in a vertical section 25^b.

5 The various track sections referred to are shown as formed of angle irons, the flanges on the track sections 21 and 22 and the extensions thereof extending toward each other to form channels; the flanges on the track section 23 and the extensions thereof extending 10 upwardly and toward the track section 22; the flanges on the track section 24 extending toward the track portion 23^d; and the flanges on the track 25 extending upwardly.

15 The rollers 16 rollingly fit within the channel provided by the tracks 21 and 22 and their extensions; the rollers 18 operate against the track 23 and its extension; and the rollers 20 against the undersides and the outer surfaces of the track 22 and its extension. The 20 arrangement of the rollers and tracks is such, as described, that in the movement of the bucket from the position shown in Fig. 1 toward dumping position, the bucket is first moved along a substantially horizontal path 25 and as its rollers 16 and 18 engage the lower inclined portions of the tracks, the bucket is partly righted and upon engaging the vertical portions of the tracks is fully righted. When the bucket rises to a point where its 30 rollers 18 and 20 engage the inclined track 24, the bucket, upon continuing its upward movement, tilts outwardly, its rollers 16 continuing their movement through a vertical path between the track portions 21^b and 22^b. 35 The rollers 18, as the rear, or bottom, portion of the bucket continues to rise, move out onto the horizontal portions 23^e of the tracks, and as the rear, or bottom, portion of the bucket continues to rise, the bucket moves at its 40 outer discharge end back toward the tower, the rollers 20 engaging with the track 25 and the rollers 18 passing beneath this track so that the bucket in the final elevating movement occupies the dotted line position represented in Fig. 1 in which it dumps its 45 contents above the track 11. In the lowering of the bucket it tilts upwardly at its discharge end, the rollers 20 running out onto the 50 track section 25 and the rollers 18 engaging the track portion 23^e, and when the rollers 16 in lowering on the tracks 21^b and 22^b move below the plane of the rollers 18, the latter move down the track section 23^d and right the 55 bucket which then continues its downward movement in righted condition until the inclined sections 21^a, 22^a, and 23^a of the tracks are reached, whereupon the bucket tilts 60 toward horizontal position which latter position is reached upon the engagement of the 65

rollers with the horizontal portions of the tracks.

The receptacle 14 may be moved into and out of the various positions stated by any suitable hoisting and lowering means such 70 for example as that shown more or less diagrammatically in the drawings and involving a hoisting machine represented generally at 75 26 which is mounted on the upper end of the tower 15 and drives sprockets 27 at opposite sides of the tower over which endless sprocket chains 28 extend. These chains extend downwardly through the tower and engage sprockets 29, 30, 31 and 32 journaled on stationary 80 parts of the apparatus to extend adjacent the inclined track sections 21^a, 22^a, and 23^a, and terminal sprockets 33 journaled in the pit 12 beyond the point to which the bucket moves, these sprocket-chains being rigidly connected 85 in any desirable way, with the ends of the shaft 16^a.

In the operation of the apparatus rotation of the drum 27 in one direction operates to move the bucket 14 from the position shown in Fig. 1 along the tracks and up into dumping 90 position, and rotation in the opposite direction returns the bucket to the position shown in this figure, any suitable means, as will be readily understood by those skilled in the art, being provided for effecting the 95 drive of this drum in opposite directions for the purpose stated.

The hopper 13 is preferably provided with valve mechanism of any suitable type, controlling its outlet, that shown comprising 100 sectional swinging gate-valves 34 movable into and out of hopper-closing position and controlled in any suitable manner, as for example from a revoluble shaft 35 having eccentric connections with valve-operating 105 levers 36 connected with the valves 34, rotation of the shaft 35 in one direction opening the gate valves and rotation in the opposite direction closing these valves.

110 It will be noted from the foregoing description that all of the rollers at each side of the bucket, are arranged in the same plane and consequently the tracks with which they cooperate are located in the same plane, due to the fact that none of these rollers are required to cross the path of other rollers in the operation of dumping the bucket, this feature being desirable from a practical standpoint as it simplifies the structure and reduces the cost of construction.

115 Furthermore, the provision of the rollers as described in combination with the inclining of the side of the bucket as shown at 17, is of advantage as the bucket may be caused to make a sharp turn, without obstruction, 120 in moving from the substantially horizontal path through which it moves on its side in the pit, to the substantially vertical path through which it moves, in righted position, 125 in moving in the tower, and thus the appa- 130

is positioned on its side and in moving along
said means moves toward righted position,
said bucket having one side partly closed and
the opposite side thereof formed of portions
extending in different planes, one of said por-
5 tions inclining toward said partly open side
and the discharge end of said bucket, said
partly closed side extending from the base of
the bucket upwardly above the base of said
inclining portion.
